UNITED STATES PATENT OFFICE.

JOSEPH H. HEISHMAN, OF CLARENDON, VIRGINIA.

GRAIN SEPARATOR.

Application filed January 27, 1923. Serial No. 615,188.

To all whom it may concern:

Be it known that I, JOSEPH H. HEISHMAN, a citizen of the United States, residing at Clarendon, in the county of Arlington and State of Virginia, have invented certain new and useful Improvements in Grain Separators, of which the following is a specification.

This invention relates to a grain separator and has for an object the provision of means for separating extraneous matter from grain, and more particularly for separating garlic and inferior or defective wheat grains from the perfect wheat grains.

Another object of this invention is to provide means for scouring or cleaning the wheat grains in order to remove the hairy substance therefrom, and especially to remove any dirt or other extraneous matter from the furrow of each wheat grain.

A further object of this invention is to provide a grain separator of generally improved construction, whereby the device will be simple, durable, and inexpensive in construction, as well as convenient, practical, serviceable and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

The invention has been illustrated in its preferred embodiments in the accompanying drawings, wherein:

Figure 1 is an elevation of the separator;

Figure 2 is a vertical sectional view, viewed at right angles to Figure 1, parts appearing in elevation; and

Figures 3, 4, 5, 6 and 7 are diagrammatic views, illustrating different phases of operation of the device.

Referring to the drawing there is shown a frame 1 having a drive shaft 2 journalled thereon. A roller or drum 3 is supported by a shaft 4 which in turn is journalled in spaced bearings 5 that are adjustably mounted on the frame, 1 as indicated at 6. This roller has a series of resilient fingers 7 extending from the periphery thereof, each finger comprising an inner section 8 and

outer section 9 which sections are disposed at an angle to each other. The inner section 8 is inclined towards the direction of rotation of the roller 3, while the sections 9 are inclined contrary to the direction of rotation of this roller. A pulley 10 is secured to the shaft 4 and is driven from a pulley 11 through the instrumentality of a crossed belt 12, thereby causing the roller 3 to rotate in a direction contrary to the direction of rotation of shaft 2. A piercing roller or drum 13 is rigidly secured to a shaft 14, which shaft is journalled in fixed bearings 15 mounted upon the frame 1. This roller has a plurality of short piercing fingers 16 extending from the periphery thereof and inclined away from the direction of rotation of the roller 13. Mounted in cooperable relation with the roller 13 is a brushing or detaching roller 17 provided with a plurality of substantially tangential yielding fingers or bristles 17' extending from its periphery and this roller is carried by a shaft 18 journalled in space bearings 19, which bearings are supported by the frame 1 and are adjustably relative thereto as indicated at 20. An idler 21 is journalled in an adjustable bearing 22 carried by a bracket 23 which is supported by the frame 1. A drive pulley 24 is rigidly secured to the shaft 2 and drives the rollers 13 and 17 through the instrumentality of a belt 25 which passes over the pulley 24, pulleys 26 and 27 mounted on shafts 14 and 18 respectively, and under the idler 21, thereby rotating the rollers 13 and 17 in the same direction and contrary to the direction of rotation of roller 3.

An inclined chute 28 is provided and terminates at its lower end at a point above the roller 3 and a hopper 29 is located immediately below the rollers 3 and 13 and terminates at its lower end in a restricted neck 30 which extends into an apron 31 upstanding from a screen housing 32. This screen housing is yieldingly supported in an inclined position by resilient straps or springs 33 preferably secured to the opposed longitudinal terminals of the screen housing 32 and are secured to and supported by the frame 1.

A screen or foraminous partition 34 separates the housing into upper and lower compartments 35 and 36, the lower compartment 36 discharging into a chute 37 and the upper compartment discharging into a conduit 38

which is provided with a series of space baffle fins 39. The lower portion of the conduit 38 communicates with a suction fan 40 through the instrumentality of a conduit 41 which is interrupted by a baffle plate 42 disposed immediately above a collecting chamber 43 having a sliding closure 44. The fan 40 is driven from a pulley 45 mounted on the shaft 2 through the medium of a belt 46 trained over the usual fan pulley 47. A conveyor tube 48 communicates with the chute 37, as indicated at 49, and a hopper 50 is formed at the upper terminal thereof, which hopper is disposed immediately below the rollers 13 and 17.

In order to impart a reciprocatory motion to the screen housing 32 there is provided a shaft 51 journalled in bearings 52 carried by the frame 1, and having an offset or crank portion 53 formed intermediate its ends. The crank portion 53 of the shaft 51 is operably connected to the screen housing by means of a link 54. A pulley 55 is carried by the shaft 51 and this pulley is driven from a pulley 56 mounted on the shaft 2, through the instrumentality of a belt 57.

In operation the grain is fed through the chute 28 and deposited on the rollers 3 and 13 which cooperate to separate the extraneous matter and defective wheat from the perfect wheat. The resilient fingers 7 of the roller 3 yield as the relatively hard unimpaired grains of wheat pass between the rollers 3 and 13 and allow them to gravitate into the hopper 29. There they are discharged onto the screen 34, and since the screen is slightly inclined and is constantly reciprocated, the wheat will be discharged from the lower end of the screen into the conduit 38. Owing to the presence of the baffle fins 39 within this conduit 38, the wheat will pass slowly therethrough and if any particle of extraneous matter accompanies the wheat it will be sucked into the conduit 41 and conveyed to any convenient point by means of the fan 40. Any relatively heavy matter that would not be readily discharged through the fan will impinge against the baffle plate 42 and drop into the collecting chamber 43 from which it can be discharged by opening the closure 44.

As the wheat passes along the screen 34, wild seed and other extraneous matter that may accompany it will gravitate through the screen into the lower compartment 36 from which they are then discharged into the chute 37 and in turn into the tube 48. Thus it is obvious that any foreign matter that may accompany the wheat into the hopper 29 will be thoroughly separated therefrom by the disclosed instrumentalities and the clean and perfect wheat will be conveyed to any suitable point from the lower terminals of the conduit 38.

If garlic or other relatively soft matter

should enter the chute with the perfect wheat, then the resilient fingers 7 will force the garlic or other soft matter against the roller 13, thereby causing the short inclined finger 16 to pierce the garlic and cause it to cling to the roller 13. Further rotation of the roller 13 will convey the garlic away from the roller 3, and bring it into engagement with the relatively long fingers or bristles 17' of the brushing or detaching roller 17, thereby releasing the garlic from the roller 13 and depositing it within the hopper 50 and then it is conveyed to any desired point through the conveyor tube 48. Should any weevil eaten or fly eaten wheat accompany the perfect wheat through the chute 28, the fingers 16 of the roller 13 will pierce into the small openings formed by the insects in this defective wheat and cause it to cling to the roller 13 and be conveyed to the detaching roller 17 and released as hereinbefore described.

Any soggy wheat that may be conveyed to the roller 13 will also be pierced by the finger 16 and conveyed to the detaching roller thereby separating this defective wheat from the perfect wheat.

The roller 3 is driven at a much higher speed than the piercing roller 13, therefore if any dirty wheat grains should be fed to these rollers, the fast moving fingers 7 of the roller 3 will tend to rotate the grains and at some time scour their surfaces, consequently removing all dirt and also removing the hairy substance usually carried by each grain. As shown diagrammatically in Figure 4, the resilient fingers 7 will also enter the furrow F of each wheat grain as it passes between the rollers 3 and 13 and scrape all extraneous matter that may be lodged within the furrow therefrom.

The operation of the rollers is diagrammatically depicted by Figure 3, in which the garlic is designated G, weevil eaten or fly eaten wheat E, soggy wheat S, and the perfect wheat grain W, in which figure it is clearly shown that the garlic and defective wheat is delivered to the hopper 50, while the perfect wheat grains are deposited into the hopper 29. Figure 5 diagrammatically shows the normal position of the fingers 7 and 16 of the rollers 3 and 13 respectively, preparatory to receiving the grains, and in the diagrammatic Figure 6 the perfect wheat grain W, is shown passing between the rollers 3 and 13, in which position the resilient fingers 7 yield towards the pressure roller 3 to permit the passage of the perfect wheat grain between these rollers. In Figure 7, a soggy grain, or a weevil eaten or wheat grain W, is shown passing between rollers 3 and 13, in which position the resilient fingers 7, due to the angular relation existing between the inner and outer sections 8 and 9 thereof, press this defective grain

towards the roller 13 with sufficient stress to cause the short fingers 16 to pierce the grain and convey it to the detaching roller.

From the foregoing it is manifest that by this arrangement all extraneous matter or imperfect wheat is separated from the perfect wheat as they pass between the rollers 13, and if any relatively small particles such as wild seed and the like should find its way to the hopper 29, they will in turn be separated from the wheat before it reaches the conduit 38 and then if any chaff or the like should be present, this will also be separated from the wheat thereby delivering only perfect wheat to the desired point through the lower end of the conduit 38.

What I claim as new is:—

1. A grain separator including a rotatable piercing roller having inclined piercing fingers extending from the periphery thereof, a pressure roller cooperating with the piercing roller and rotatable at a different speed than the piercing roller so as to cause components of the pressure roller to exert a stress towards the piercing roller in the direction of the length of the cooperating piercing fingers.

2. A grain separator including a rotatable piercing roller having inclined fingers extending from the periphery thereof, a pressure roller cooperating with the piercing roller, and means for causing components of the pressure roller to exert a stress towards the piercing roller in the direction of the length of the cooperating piercing fingers.

3. A grain separator including a rotatable piercing roller having inclined fingers extending from the periphery thereof, means cooperating with the piercing roller for exerting a stress towards the piercing roller in the direction of the length of the cooperating piercing fingers to attach defective grain and extraneous matter to the piercing fingers, and means for detaching the said matter from the piercing fingers.

4. A grain separator including a rotatable piercing roller having inclined piercing fingers extending from the periphery thereof in a direction contrary to the direction of rotation of the roller, a yielding pressure roller cooperating with the piercing roller and rotatable in a direction towards the piercing roller at a greater peripheral speed than the peripheral speed of the piercing roller to thereby exert a yielding stress towards the piercing roller in the direction of the length of the tangential piercing fingers to attach defective grain and extraneous matter to the piercing fingers, and means for detaching the defective grain and extraneous matter from the piercing fingers.

5. A grain separator including a piercing

roller, piercing fingers extending from the periphery of the piercing roller and disposed at a tangent to the periphery of the roller in a direction contrary to the direction of rotation of the piercing roller, a pressure roller mounted in cooperable relation to the piercing roller, pressure fingers extending from the periphery of the pressure roller, said fingers being formed with inner and outer sections, the inner section of each finger being disposed at a tangent to the pressure roller in the direction of rotation of the pressure roller and the outer section of each finger being disposed at an angle to the inner section in a direction away from the direction of rotation of the pressure roller, the pressure fingers cooperating with the piercing fingers to separate defective grain from the perfect grain and to separate extraneous matter from the perfect grain.

6. A grain separator including a piercing roller, piercing fingers carried by the periphery of the piercing roller and disposed at a tangent thereto, a pressure roller mounted to cooperate with the piercing roller, resilient fingers extending from the periphery of pressure roller, each finger being formed of inner and outer sections disposed at an angle to each other, means for conveying grain to the piercing and pressure rollers, the resilient fingers of the pressure roller yielding to permit the perfect grain to pass between said rollers and constructed to exert sufficient stress upon defective grain and extraneous matter to cause the piercing fingers to pierce the defective grain or extraneous matter thereby securing it to the piercing roller, and means for detaching the defective grain and extraneous matter from the piercing roller at a point remote from the pressure roller.

7. A grain separator including a rotatable piercing roller having inclined piercing fingers extending from the periphery thereof in a direction contrary to the direction of rotation of the roller, a yieldable pressure roller rotatable in a direction towards the piercing roller and cooperating with the piercing fingers to attach defective grain and extraneous matter to the piercing fingers, and a detaching roller rotatable towards the piercing roller and cooperating with the piercing fingers to detach the defective grain and extraneous matter from the piercing fingers.

8. A grain separator including a rotatable piercing roller having inclined piercing fingers extending therefrom in a direction contrary to the direction of rotation of the roller, a yieldable pressure roller cooperating with the piercing roller and rotatable in a direction towards the piercing roller at a greater peripheral speed than the peripheral speed of the piercing roller, and a de-

6 taching roller cooperating with the piercing roller and rotatable in a direction towards the piercing roller at a greater peripheral speed than the peripheral speed of the piercing roller.

9. A grain separator including a piercing roller, piercing fingers carried by the piercing roller, a pressure roller mounted to cooperate with the piercing roller, resilient fingers extending from the pressure roller and each finger being formed of inner and outer sections disposed at an angle to each other so as to exert a yielding stress towards the pressure roller to attach defective grain and extraneous matter to the piercing fingers.

10. A grain separator including a rotatable piercing roller having inclined fingers extending from the periphery thereof, a 20 pressure roller rotatable towards the piercing roller and cooperating with the piercing roller to attach matter to the piercing fingers, and a detaching roller rotatable towards the piercing roller and having tangential fingers extending therefrom to cooperate with the piercing fingers to detach the said matter therefrom,

11. A grain separator including cooper-

ating rollers for separating perfect grain and relatively hard extraneous matter from defective grain and relatively soft extraneous matter, means for depositing the perfect grain and relatively hard extraneous matter into one conveying means, and the defective grain and relatively soft extraneous matter into a separate conveying means, means for separating the relatively hard extraneous matter from the perfect grain and to convey it to the same conveying means into which the defective grain is deposited.

12. A grain separator including cooperating rollers for separating perfect grain and extraneous matter from defective grain, means for depositing the perfect grain and extraneous matter into one conveyor, and the defective grain into a separate conveyor, means for separating the extraneous matter from the perfect grain and to convey the extraneous matter to the same conveying means into which the defective grain is deposited.

In testimony whereof I affix my signature.

JOSEPH H. HEISHMAN.
